UNITED STATES PATENT OFFICE.

ISAAC PERAL, OF SAN FERNANDO, SPAIN.

REFLECTOR.

SPECIFICATION forming part of Letters Patent No. 445,379, dated January 27, 1891.

Application filed March 18, 1888. Serial No. 274,292. (No model.) Patented in Spain April 26, 1888, No. 7,975.

To all whom it may concern:

Be it known that I, ISAAC PERAL, a citizen of the Kingdom of Spain, residing at San Fernando, in Spain, have invented certain new and 5 useful Improvements in Reflectors, (for which I have obtained a patent in Spain, No. 7,975, dated April 26, 1888,) of which the following is a specification.

The object of the present invention is to 10 utilize nearly all of the light-rays for effective illuminating purposes, thus lessening the number of rays which are lost by being projected in such direction as to prevent their being utilized, while increasing the effectiveness of the light and reducing the amount 15 of energy required to produce the same.

In the accompanying drawings, Figure 1 is a diagram of the system and the respective arrangements of the reflectors. Fig. 2 represents 20 the back of the reflector. Fig. 3 is a vertical section showing the interior of the reflector. Fig. 4 represents the same reflector with an arrangement to light the whole of the horizon.

25 In Fig. 1, $a b c d$ is a parabolic reflector, the focus of which is in f , and $e g h l$ is a supplemental hemispherical reflector, the center of which is also in f . These reflectors are so arranged that the diameter $c l$ of the hemispherical reflector, the focus f , and the line $a d$ of the main parabolic reflector are in the same plane. All the rays of light included 30 within the angles $b f a$ and $c f d$ will, because of the parabolic form of the main reflector, be reflected parallel, and the beam of light 35 will be represented by a hollow cylinder, the outer lines of which are $a a'$ and $d d'$ and the inner lines $b b'$ and $c c'$, and this beam shall be called in the following specification the 40 "outer beam." By examining the hemispherical supplemental reflector it will be seen that all the rays of light within the angles $e f g$ and $l f h$ will be reflected on the surface of the parabolic reflector within the angles $c f d$ and $b f a$, respectively, thus serving to intensify 45 the above-described outer beam.

By further examining Fig. 1 it will be seen that the whole luminous sphere emitted from the focus f is utilized with the exception of 50 the cones, which have their apex in f and are within the angles $b f c$ and $g f h$. It is also

evident that the cone of light represented by $f b c$ would be reflected in a beam representing a full cylinder filling the hollow of the outer beam. If it were not for the interposition 55 of the supplemental hemispherical reflector, the same would take place with the cone of light $f g h$. For the purpose of also utilizing this quantity of light, and because the cone of light $f g h$ is perfectly useless for the production of the outer beam, the part $g h$ of the hemispheric reflector is cut out. Thus the cone of light $f g h$ passes unreflected through this opening, and if now the part $b g c$ of the main parabolic reflector is replaced by a 60 spheric part $b p c$, struck from the center f , the rays reflected from this would mingle with and intensify the cone $f g h$. This would form a diverging beam; but by inserting, for instance, a biconvex lens x , having its focus 65 in f , this diverging beam would be transformed into a cylindrical one called the "inner beam," which fills the dark hollow of the outer beam.

From the foregoing it is evident that theoretically not a single ray is lost, with the exception of the small quantity intercepted by the carbons producing the light; but this is reduced to a minimum by the peculiar arrangement of the carbons in this apparatus. 70

In reflectors for reflecting rays of light on parallel lines heretofore in use the carbons and carbon-holders have been so mounted as to lie in planes transverse to the direction of the parallel reflected rays. In this apparatus 75 the carbons are mounted so as to lie parallel to such rays along the line $m n$, Fig. 1, and thus the cone of maximum intensity will fall on the efficacious part of the reflector. The positive carbon is mounted opposite the parabolic reflector. This arrangement of the carbon-holders in itself suffices to increase the efficiency of the reflector; but in combination with the two reflectors described above it is still further increased, especially as the 80 shadow thrown by the carbons falls in the least efficient part of the sphere of light—i.e., the inner beam. This arrangement of the carbons further facilitates the crossing of the rays through the focus mentioned above, and 85 the carbon holders and fittings are arranged in the cylinder representing the inner beam.

Thus the quantity of light intercepted by the carbons is reduced to a minimum.

The carbon-holders and mechanism for operating them are represented in Figs. 2 and 3. To intercept the least possible light the support and mechanism for operating the negative carbon N are placed at the back of the reflector A, which is formed with a central opening just large enough to let the carbon and the carbon-holder pass. This carbon-holder is, as represented in the drawings, attached to a mechanism permitting the adjustment of the negative carbon, and consequently the adjustment of the arc.

15 The movement of the positive carbon P is simultaneous with that of the negative carbon and is effected by the mechanism represented in the drawings. The positive carbon passes through an opening formed in the above-mentioned lens of the hemispheric reflector. This lens may also be omitted, as the diverging rays would serve to lighten up the shadow thrown by the carbons in the inner beam.

20 25 The mechanism is constructed in such a manner that the rate of advance of the positive carbon is twice that of the negative, because of the positive carbon being consumed about twice as quick as the negative, and thus the arc always remains adjusted in the focus.

If it is desired to produce a diverging beam, so as to extend the lighted space, it is only necessary to remove the arc from the focus of the parabolic reflector in the direction of its axis, and for this purpose the mechanism for moving the negative-carbon holder is provided with a second hollow screw V, which is traversed longitudinally by the screw B and 30 by which the position of the negative carbon can be altered independently of the simultaneous movement of the positive carbon.

The arrangement of the electric contacts and of the insulators need not be described, 35 as it is of the usual form.

40 To prevent the reflectors from being distorted by the heat produced by the arc they are strengthened at the back with radial ribs.

The hemispheric reflector is held in position by the frame D, which also carries the positive-carbon holder, and is as thin as possible to intercept as little light as possible. The position of this hemispheric reflector is slightly adjustable, so as to permit the proper 45 adjustment of the focus.

The whole apparatus is journaled in a stand F, the axis through the journals T going through the center of gravity of the apparatus, which can be turned completely round this 50 axis.

The above-described arrangements are not the only ones which render this apparatus new and useful in many instances, such as for war-ships and fortifications in time of war or for vessels of any description wanting to 55 enter a port during the night. As it is often necessary to light the greatest part of the

horizon simultaneously, a supplementary reflector may be used with the above-described apparatus, which will light simultaneously the whole horizon, if desired. Supposing the parabolic reflector is turned in its stand on the horizontal pivot T until its axis stands vertical, as represented in Fig. 4, the beam of light will be reflected toward the zenith; but if this beam is intercepted by a conical reflector R, the sides of which form an angle of forty-five degrees with the horizontal line, this cylindrical beam of light will be converted into a disk of light lighting up the whole horizon.

60 The immense advantages and various applications of this arrangement are easily understood, especially as regards war-ships and the merchant navy. A war-ship provided with several reflectors throwing parallel beams may be surprised by a torpedo-boat while another side is being searched with the reflectors, while with the disk of light thrown by the supplementary reflector the whole horizon is lighted and all enemies can be watched simultaneously.

65 The mechanical arrangement is very simple. A hollow cone R of the above-mentioned angle provided with the necessary strengthening ribs to prevent distortion is placed with its apex toward the interior of the reflector, the axis of both in the same line. The base of the cone has the same diameter as the reflector A. Three thin equidistant rods C are attached to the base of the cone, and to the other end of these rods is fastened a ring H, formed with several notches, which engage like a bayonet-joint with corresponding catches on the outer rim of the reflector. It 70 will easily be understood now how easy it will be to adjust or remove the conical reflector for transforming the cylindrical beam into a disk of light or vice versa.

Having now particularly described and ascertained the nature of my said invention and in what manner the same is to be performed, I declare that what I claim is—

1. The combination of the main parabolic reflector, the burner situated in the focus thereof, and the supplemental hemispherical reflector of smaller size than and situated opposite to and facing the main reflector and arranged to focus at the burner and having its central portion cut away to permit the passage of certain of the direct rays from the burner, substantially as described.

2. The combination, with the burner, of the main reflector consisting of the outer parabolic portion and the central spherical portion, and the supplemental spherical reflector situated opposite to and facing the spherical portion of the main reflector and having its central portion cut away, whereby the rays reflected from the spherical portion of the main reflector may pass the supplemental reflector, substantially as described.

3. The combination, with the burner, of the main reflector consisting of the outer para-

bolic portion and the central spherical portion, the supplemental reflector situated opposite to the spherical portion of the main reflector and having its central portion cut 5 away, whereby the rays reflected from the spherical portion of the main reflector may pass the supplemental reflector, and a lens situated in the path of such reflected rays for making them parallel, substantially as described.

4. The combination, with the main parabolic reflector and a supplemental spherical reflector, each centrally perforated for the

passage of electric-light carbons and arranged opposite to each other, the foci of the said reflectors coinciding of an electric-arc light arranged at the focal point and having its carbons arranged parallel with the axis of the parabolic reflector, substantially as described.

In testimony whereof I have hereunto subscribed my hand in the presence of the two 20 subscribing witnesses.

ISAAC PERAL.
